DESIGN FOR A SLED DECK

James M. Bowen, Cape May Court House, N. J., assignor to S. L. Allen & Co., Inc., Philadelphia,
Pa., a corporation of Pennsylvania

Application April 6, 1934, Serial No. 51,330

Term of patent 14 years

To all whom it may concern:

Be it known that I, JAMES M. BOWEN, a citizen of the United States, residing in Cape May Court House, county of Cape May, and State of New Jersey, have invented a new, original, and ornamental Design for a Sled Deck, of which the following is a specification, reference being had to the accompanying drawing, forming a part thereof.

The figure is a top plan view of a sled deck, showing my new design.

I claim:

The ornamental design for a sled deck substantially as shown.

JAMES M. BOWEN.
